United States Patent

Des. 234,955
Patented Apr. 22, 1975

234,955

MAGNETIC DISC MEMORY SYSTEM

Charles Koster, Sepulveda, Calif., assignor to
OMI Memories, Inc.

Filed Jan. 30, 1973, Ser. No. 328,037

Term of patent 14 years

Int. Cl. D14—02
U.S. Cl. D26—5 C

FIG. — 1

FIG. — 3

FIG. — 2

FIG. — 4

FIG. — 5

FIG. — 6

FIG. — 7

FIG. 1 is a perspective view showing the front, top and right side of my magnetic disc memory system;

FIG. 2 is a perspective view showing the top, rear and right side thereof;

FIG. 3 is a front view thereof;

FIG. 4 is a rear view thereof;

FIG. 5 is a top view thereof;

FIG. 6 is a right side view thereof; and

FIG. 7 is a left side view thereof.

The net like pattern on the front central portion of the article is understood to repeat throughout the indicated area. Similarly, the pattern of perforations on the rear of the article repeats throughout the indicated areas. The bottom of the article is unornamented.

I claim:

The ornamental design for a magnetic disc memory system, substantially as shown and described.
